UNITED STATES PATENT OFFICE.

ETHAN I. DODDS, OF PITTSBURGH, PENNSYLVANIA, ASSIGNOR TO FLANNERY BOLT COMPANY, OF PITTSBURGH, PENNSYLVANIA.

STAYBOLT STRUCTURE.

1,390,279.

Specification of Letters Patent. Patented Sept. 13, 1921.

Application filed January 20, 1920. Serial No. 352,694.

To all whom it may concern:

Be it known that I, ETHAN I. DODDS, a citizen of the United States, and a resident of Pittsburgh, in the county of Allegheny and State of Pennsylvania, have invented certain new and useful Improvements in Staybolt Structures; and I do hereby declare the following to be a full, clear, and exact description of the invention, such as will enable others skilled in the art to which it app-

10 pertains to make and use the same.

This invention relates to improvements in staybolt structures for boilers,—one object of the invention being to provide a bearing member for the head of a staybolt which may be mounted in the boiler sheet so that its outer end will be flush with the latter and so that said bearing member may be adjusted before being fixed to the boiler sheet, 15 or to mount said bearing member so that it shall be universally adjustable and project beyond the outer face of the boiler sheet.

With this and other objects in view, the invention consists in certain novel features 20 of construction and combinations of parts as hereinafter set forth and pointed out in the claims.

In the accompanying drawings, Figure 1 is a sectional view partly in elevation showing 25 an embodiment of my invention with the outer end of the device flush with the outer face of the outer boiler sheet; and Figs. 2 to 6 are views illustrating modifications.

1 represents an outer boiler sheet and 2 30 the inner sheet, with which latter the inner end of a staybolt 3 is connected in any suitable manner and the outer headed end 4 of the staybolt is connected with the outer boiler sheet as hereinafter described.

40 In Fig. 1 the outer boiler sheet is shown as provided with an opening 5, a portion of which may be cylindrical. Inwardly removed from the outer face of the boiler sheet 1, the wall of the opening is recessed as 45 at 6 thereby forming a shoulder 7 and from this recessed portion the wall of the opening may be made flaring as shown at 8.

A bearing sleeve 9 (preferably having an 50 exteriorly rounded portion 16) passes through the opening in the boiler sheet and has an external diameter appreciable less than the diameter of the opening 5. The sleeve 9 is provided at its outer end with a lateral flange 10, between the under face of which

and the shoulder 7 formed by the recess 6, a 55 ring 11, preferably of metal is disposed. This ring is of such internal diameter as to neatly fit around the bearing member under the flange 10 and is appreciably less in external diameter than is the diameter of that 60 portion of the opening in the boiler sheet formed by the recess 6 so that the bearing member may have more or less lateral adjustment.

The bearing member 9 is provided interiorly with a rounded seat 12 on which the head 4 of the staybolt is mounted and the outer end portion of the bearing member is threaded interiorly to receive a closure 13 which is so formed as to provide a clearance 65 space 14 for the bolt head. It will be observed that the outer end of the bearing member 9 and the outer end of the closure 13 are substantially flush with each other and with the outer face of the boiler sheet 1. 75

The space between the peripheral portion of the flange 10 and the beveled or flaring portion 8 of the wall of the opening in the boiler sheet is occupied by a weld 15 which may cohere, not only with the bearing member and boiler sheet but also with the ring 11 and thus the bearing member will be fixedly united to the boiler sheet 1. 80

In the embodiment of the invention shown in Fig. 2, 1^a represents an outer boiler sheet 85 and 2^a the inner sheet of a boiler. A staybolt 3^a is secured in any suitable manner to the inner sheet 2^a and is provided at its outer end with a head 4^a which is connected with the outer sheet as hereinafter described. 90

A bearing member 5^a is provided to receive the head at the outer end of the staybolt and through the medium of which the staybolt is connected with the boiler sheet. 95

The bearing member 5^a is made hollow to receive the head of the bolt and after said head shall have been inserted into the member 5^a, the inner end portion of the latter will be forged so as to inclose the head of the bolt, at the same time providing an interior curved seat 6^a for the head of the bolt and also an external curved portion 7^a. The bolt and bearing member may be assembled as above described at the shop. The interior of the member 5^a has such configuration 100 and proportions as to provide a clearance space 8^a for the bolt head and the closed end 9^a of said member 5^a constitutes a closure 105

over the bolt head. The outer closed end of the member 5^a may be made with an angular recess 10^a for the reception of a wrench.

The bearing member 5^a is provided exteriorly, near its outer end with screw threads 11^a, and at its outer end, said bearing member is provided with an annular flange or shoulder 12^a.

When a "flush" mounting is desired, a bearing ring 13^a is screwed on the threaded portion of the bearing member 5^a and this ring is made with a countersunk seat 14^a for the annular flange or shoulder of the bearing member 5^a. The bearing ring 13^a is made rounded exteriorly as at 15^a to have universally movable mounting on a rounded seat 16^a formed by a portion of the wall of an opening 17^a in the outer boiler sheet, so that the bearing member may be so adjusted as to insure proper alignment of the staybolt with its points of connection with the respective boiler sheets. The bearing ring 13^a is beveled at its upper end, as at 18^a, and this beveled portion forms, with a portion of the wall of the opening in the boiler sheet, a groove in which a weld 19^a is located,—said weld fixedly uniting the bearing ring to the boiler sheet when the parts shall have been properly adjusted.

With the parts assembled as above described the bolt may be tested by attempting to turn the bearing member in a direction to produce a pull on the bolt. Should the bolt be broken, the bearing member can be turned.

In the embodiment of the invention shown in Figs. 3 and 6, 1^b represents an outer boiler sheet having an opening 2^b, the wall of which may be straight and cylindrical. The inner boiler sheet is indicated at 3^b and with said sheet 3^b, the inner end of a staybolt 4^b is connected in any suitable manner, the outer end of said staybolt being provided with a rounded head 5^b which is connected with the outer boiler sheet 1^b by means of devices hereinafter described.

6^b represents a bearing member, the major portion of which is partly spherical and hollow while the outer end portion is enlarged as at 7^b and provided with an annular flange 8^b. The blank from which the member 6^b is made is slotted or slit as indicated by dotted line 9^b and after the head of the bolt shall be inserted into said member, the inner portion of the latter will be pressed by a forging operation so as to inclose the bolt head and provide a seat 10^b for the latter. The interior of the member 6^b has such configuration and proportions as to provide a clearance space 11^b for the bolt head, and the larger end 7^b of said member is provided with an opening which communicates with the space 11^b whereby access may be had to the head of the staybolt for testing the latter. The wall of the opening in the en-

larged outer or head portion 7^b of the member 6^b is threaded and receives a threaded plug 12^b which normally closes said opening. This plug may be made with an angular recess 13^b to receive a wrench.

A ring 14^b is mounted on the outer face of the boiler sheet 1^b surrounding the opening 2^b and overlies said opening. This ring affords a seat on which the annular flange 8^b of the bearing member 6^b rests. The internal diameter of the ring 14^b is slightly greater than the external diameter of that portion of the bearing member which it surrounds, thus leaving a clearance space 15^b.

A weld 16^b surrounds the ring 14^b and also the flange 8^b of the bearing member and unites said ring and bearing member to the outer face of the boiler sheet.

It will be observed that the opening 2^b in the boiler sheet is straight and that the bearing member is connected with the outer face of the boiler sheet and thus necessity for threading or reaming the boiler sheet to accommodate the bearing members is obviated.

By reason of the rounded contour of the body portion of the bearing member, the latter may be mounted on a seat in the boiler sheet so as to be universally movable or adjustable if desired.

Instead of making the under face of the flange 8^b of the bearing member flat, said flange may be rounded as indicated at 17^b. Fig. 4 and the ring 14^b may be made with a rounded seat 18^b to receive the rounded portion 17^b of the flange.

The bearing member 6^b as shown in both Figs. 3 and 4 of the drawing is capable of limited movement on the ring 14^b for adjusting said bearing member before the parts shall have been welded to the boiler sheet.

In the embodiment of the invention shown in Figs. 5 and 6 1^c represents an inner boiler sheet with which the inner end of a staybolt 2^c is connected in any suitable manner and the outer end of the staybolt is provided with a rounded head 3^c which is connected with the outer boiler sheet 4^c as hereinafter described.

The boiler sheet 4^c is provided with an opening, a portion of the wall of which may be rounded to provide a seat 5^c and the outer portion of said opening may be enlarged to form an annular recess 6^c adjacent to the outer face of the boiler sheet.

A ring 7^c is located on the outer face of the boiler sheet 4^c and has an interior threaded portion 8^c which overlies the annular recess 6^c in the boiler sheet. This ring is fixedly united to the boiler sheet 4^c by means of a weld 9^c—the alloy composing this weld surrounding said ring and extending to the outer face of the boiler sheet 4^c so as to cohere to both.

A combined bearing member and closure

10° enters the opening in the boiler sheet and that portion of said member which passes through the boiler sheet is rounded so as to conform to the seat 5° in the boiler 5 sheet and so as to permanently inclose the bolt head 3° and provide a seat 11° for said bolt head. The interior contour of the member 10° is such as to provide a clearance space 12° for the head of the staybolt.

10 The member 10° is made with an external threaded portion 13° which screws through the threaded ring 7° and with a peripheral flange 14 which overlies said ring,—a gasket 15° being interposed between said peripheral flange and said ring. The member 15 10° is also provided with an angular head 16° to receive a wrench.

With the use of the structure an efficient mounting is provided for the head of the 20 staybolt and a convenient connection is afforded for the staybolt to the boiler sheet which will permit the testing of the staybolt by turning the member 10° without the necessity of a threaded connection between 25 said member and the wall of the opening in the boiler sheet,—said threaded connection between the member 10° and the boiler sheet being effected through the medium of the ring 7° welded to the outer face of said 30 boiler sheet.

When my improvements are applied to a curved or rounded boiler sheet 4°, the ring 7° will bear at two diametrically opposite points only against the outer face of such 35 boiler sheet, but the weld 9° will effectually unite those portions of the ring which do not contact with the face of the boiler sheet as well as those parts which do, to the boiler sheet.

40 Having fully described my invention what I claim as new and desire to secure by Letters-Patent, is:—

1. In a staybolt structure, the combination with a boiler sheet having an opening, and 45 a staybolt having a head, of a bearing member having an exteriorly rounded inner end portion and a lateral flange at its outer end, said bearing member disposed coincident with the opening in the boiler sheet and having therein a seat for the head of the staybolt, a part at the outer end of the bearing member closing the latter over the head of the staybolt, a ring between said lateral flange and the boiler sheet, and means for 55 securing said ring to the boiler sheet.

2. In a staybolt structure, the combination with a boiler sheet having an opening, and

a staybolt having a head, of a bearing member having an externally rounded inner end portion and having therein a seat for the head of the staybolt, said bearing member having a flange at its outer end, and a ring disposed between said flange and the boiler sheet and welded to the latter.

3. In a staybolt structure, the combination 65 with a boiler sheet having an opening and a staybolt having a head, of a bearing member having therein a seat for the head of the staybolt, said bearing member having a flange at its outer end, and a ring disposed 70 between said flange and the boiler sheet and secured to both.

4. In a staybolt structure, the combination 75 with a boiler sheet having an opening and a staybolt having a head, of a bearing member having therein a seat for the head of the staybolt, said bearing member having a flange at its outer end, and a ring encircling the bearing member under said flange and welded to the latter and to the boiler 80 sheet.

5. In a staybolt structure, the combination 85 with an outer boiler sheet having an opening, a portion of the wall of which is recessed forming a shoulder, of a bearing member passing through said opening and having a lateral flange near its outer end, a ring disposed between said lateral flange and the shoulder in the boiler sheet, said bearing member having an internal seat, a staybolt 90 having a head mounted on said sheet, and a weld between the peripheral portion of the flange of the bearing member and a portion of the wall of the opening in the boiler sheet.

6. In a staybolt structure, the combination 95 with a boiler sheet having an opening, a portion of the wall of which is recessed forming a shoulder, of a bearing member passing through said opening and having an 100 external diameter appreciably less than the diameter of said opening, said bearing member having a lateral flange near its outer end, a ring encircling the bearing member under said flange and resting on the shoulder 105 in the boiler sheet, said ring having an external diameter appreciably less than the diameter of the recessed portion of the wall of the opening in the boiler sheet, a weld uniting the flange on the bearing member 110 with the boiler sheet, said weld disposed over a portion of said ring, and a closure entering said bearing member.

ETHAN I. DODDS.
